UNITED STATES PATENT OFFICE

113,421

DESIGN FOR AN ELECTRIC IRON

James J. Gough, Chicago, Ill.

Application December 5, 1938, Serial No. 81,589

Term of patent 7 years

To all whom it may concern:

Be it known that I, James J. Gough, a citizen of the United States, residing at 6333 West Sixty-fifth Street, Chicago, Illinois, have invented a new, original, and ornamental Design for an Electric Iron, of which the following is a specification, reference being had to the accompanying drawing, forming a part thereof.

Figure 1 is a perspective view of an electric iron showing my design;

Figure 2 is a perspective view thereof, with the handle in lowered position; and

Figure 3 is a side elevational view of the electric iron as shown in Figure 1.

The dominant feature of my design resides in the portions illustrated in solid lines.

I claim:

The ornamental design for an electric iron, substantially as shown and described.

JAMES J. GOUGH.
